UNITED STATES PATENT OFFICE.

JOHN B. DOWNING, OF NEWARK, NEW JERSEY, ASSIGNOR TO BEAVER MACHINE & TOOL COMPANY, OF NEWARK, NEW JERSEY, A CORPORATION OF NEW JERSEY.

SWITCH PLUG.

Application filed October 10, 1921. Serial No. 506,794.

To all whom it may concern:

Be it known that I, JOHN B. DOWNING, a citizen of the United States, residing at Newark, in the county of Essex and State of New Jersey, have invented an Improvement in Switch Plugs, of which the following is a specification.

This invention relates to a switch plug particularly adapted for use in connection with electric sadirons, although of course, as will be understood, it is not limited to this particular use. Heretofore, so far as I am aware, in the use of plugs for connecting sadirons in an electric circuit, various forms of difficulties have been experienced.

Among these no provision has been made in the plug or adjacent the iron, for making and breaking the electric circuit therethrough and this has necessitated the pulling of the plug at a wall or lamp socket or other place of connection or of opening a switch at some distant point. Then again while it has been customary to employ a helical guard wire spring to protect the lead wires as the same enter the plug these have usually been clamped in position in a more or less unsatisfactory manner so as to readily work loose and get out of place; and still furthermore the lead wires as connected to the terminals in plugs of this type are so threaded in the plug as to lead directly to the terminal and to cause the pull on the lead wire in the use of the iron to be transmitted directly to the terminal connection of the lead wire; in other forms of plugs the plug socket connections have usually been made to receive a particular type of terminal made on the iron for which the plug is designed for use so that the plugs are not adapted for use with any iron except the one intended. The objects of my invention are to overcome these difficulties and in so doing provide a plug in which a switch is directly embodied in the casing of the plug to enable the operator to make and break the current at the plug. I also employ a helically coiled spring guard with a flared end adapted to be received in a recess provided therefor in the parts of the body at the plug so as to be securely fastened in position when the parts of the body of the plug are connected, and the construction is also such that the lead wires are conveyed around corners or shoulders provided therefor in the plug before being attached

to the terminals so that the pull necessarily exerted on the lead wires in the use of the plug is not conveyed directly to the terminal and the plug terminals are so constructed, as hereinafter described, as to be adapted to receive plugs of any cross sectional configuration so that the switch plug may be universally used—that is, is adapted for use with any form of electric sadiron.

In the drawing:

Fig. 1 is a plan of the base of the plug with the operative parts shown in position therein.

Fig. 2 is a similar plan with the switch member and one of the lead terminals and plug terminals removed.

Fig. 3 is a plan of the reverse side of the switch device showing the manner in which one of the lead terminals and one of the plug terminals is connected thereto.

Fig. 4 is a plan of the switch plug with the parts assembled.

Fig. 5 is a side view and partial cross section illustrating the construction of the plug terminals, and

Fig. 6 is a side elevation of the switch device and the parts associated therewith.

Referring to the drawing my improved switch plug includes a casing which is made of any suitable insulating material and is preferably divided longitudinally so as to include a base 10 and a cover 11 therefor. These parts of the casing may be connected by screws 12 and 13 passing therethrough or otherwise. In the base 10 there is a recess 14 adapted to receive a switch block 15 which, with the switch mechanism mounted thereon and the parts connected thereto as hereinafter described, is entirely removable from the base, although, as will be understood, the invention is not limited to this particular construction nor to the construction of the switch as shown because other forms of switch may be employed without departing from the nature and spirit of the invention. As illustrated, however, the switch mechanism includes a bridge 16 which is secured to the base block 15 by rivets 17 or otherwise and an oscillating member 18 together with a reciprocating member 19.

To the reciprocating member 19 there are connected buttons 20 and 21 by which the reciprocating member is operated so that through the resilient member 22 the reciprocating member operates the oscillating mem-

ber in order to make and break an electric circuit. In the position shown in Fig. 1, the parts are in the broken circuit position and when swung to the opposite position the oscillating member 18 bears against contacts 23 and 24 suitably secured in the base block 15 of the switch to close the circuit.

One of the lead wire terminals is indicated at 25. This, when the parts are in position, is adapted to have one end thereof lie within a recess 26 on the under side of the switch base block and is connected by a rivet 27 or otherwise to the contact 23. At its opposite or free end this lead wire terminal is provided with a screw 28 by which the end of the lead wire may be securely connected thereto. One of the plug terminals is indicated at 29. This is adapted at one end to lie within a recess provided therefor in the under surface of the switch base block as indicated at 30 and is preferably connected by a rivet 31 or otherwise to the contact 24. Connected to the socket terminal 29 is one of the plug sockets. Each of these comprises an obverse member and a reverse member. The obverse member is indicated at 32 and the reverse member at 33. The inner end of the reverse member 33 is provided with flanges 34 between which is received the end of the socket terminal 29 and also the corresponding end of the obverse member 32, these parts being then connected by a screw 35, the end of which is up set as indicated at 36 to securely and permanently connect these parts in this position.

Together with the recess 14 provided in the base for the switch block there are recesses 37 and 38 to receive the lead terminal 25 and the binding screw 28. In the base 10 there are also recesses 39, 40 and 41 to receive respectively the screw 35, the tongue cut from the reverse member, as hereinafter described, and the end of the reverse member when moved to receive a terminal as is also hereinafter described.

The parts herein before described include the switch mechanism at which an electric circuit may be made and broken between one lead terminal and the plug socket connected thereto. The device also includes a second lead terminal for the other lead wire and a second plug socket for the other terminal of the iron or other apparatus with which the switch plug is to be used. The second lead terminal is indicated at 42 and is provided with a screw or other connection 43 by which the second lead wire is connected thereto. This lead terminal is secured to or made integral with a connector 44 extending in a recess in the base 10 beneath the switch block 15 to the opposite side of the base 10 where the same is connected to the other plug socket made in all respects similar to the plug socket hereinbefore described, the recesses in the base

member being also similarly formed to receive the second plug socket, the recesses having the tapered faces being indicated at 45 and the recess to receive the end of a plug socket at 46, the recess 45 corresponding with the recess 40 and the recess 46 to the recess 41.

As clearly indicated in the drawing both the obverse and reverse members of both of the plug sockets are formed with a spring tongue 47 in the angular portion and extending longitudinally thereof. As shown in Fig. 5 the outer portions of the obverse and reverse members of each of the plug sockets are normally in contact with each other and these parts are appreciably spread between these points of contact and the connections between the same and the socket terminals, while the spring tongues 47 lie in the recesses 40 and 45, it being understood that there are similar recesses formed in the cover for the other parts, that is the obverse members of the plug sockets. By this construction when a plug is inserted in the plug socket the parts thereof yieldingly spread to form a frictional engagement with the plug and are at all times maintained in position relatively to the recesses provided therefor by the spring tongues 47, it being understood, of course, that the members of the plug socket are turned to their normal positions by the resiliency thereof when the plugs are removed therefrom.

The base 10 at one end thereof is provided with a semi-circular recess 48 terminating in a groove 49, and the cover is provided with a similar and corresponding recess and groove adapted to receive respectively the guard spring 50 and the flared end 51 thereof so that when the parts of the plug switch are connected the flared end 51 fitting within the groove 49 securely maintains the guard spring 50 in position making it impossible to remove the same without separating the parts of the switch or breaking either switch part or the guard spring. As will be understood the lead wires are passed through the flared spring which protects the same and are carried respectively and connected to the lead terminals 25 and 42, being carried through recesses 52 and 53 and caused to abut against shoulders 54 and 55 which act as abutments or anchorages to prevent the strain necessarily applied to these lead wires from being communicated directly to the binding screws 28 and 43 by which they are connected to the lead terminals 25 and 42.

It will now be apparent that the parts of the switch mechanism and the plug socket connected therewith, as well as the other plug socket and its lead terminal, may be separately removed from the casing so as to connect the lead wires thereto, and when thus connected the lead terminal 42 and the

plug socket associated therewith may be readily placed in position in the base, then the switch device with its lead terminal and plug socket may be placed in position in the 5 base and the cover applied and secured in position by the connecting screws 12 and 13 or otherwise when the switch plug will be ready for use.

I claim as my invention:

- 10 1. A switch plug comprising a casing, a unit removable from the casing including a switch, a lead wire terminal and a plug socket, and a second unit also removable as such from the casing including a second 15 lead wire terminal, a second plug socket and a conductor connecting the said second lead wire terminal and second plug socket.
- 20 2. A switch plug comprising a divided casing, a unit including a switch, a lead wire terminal and a plug socket adapted to be received in recesses provided in the casing and to be removable as a unit therefrom, and a second unit including a second lead wire terminal, a second plug socket and a 25 conductor connecting the said second lead wire terminal and second plug socket which are also adapted to be received in recesses provided therefor in the said casing and are removable therefrom as a unit.
- 30 3. A switch plug comprising a longitudinally divided casing, a unit including a switch, a lead wire terminal connected to one terminal of the switch, a plug socket connected to the other terminal of the

switch, the said parts comprising the unit 35 being adapted to be received in recesses provided therefor in the said casing and to be removable therefrom as such, and a second unit including a second lead wire terminal, 40 a second plug socket and a conductor connecting the said second lead wire terminal and plug socket and also adapted to be received in recesses provided therefor in the said casing and to be removable therefrom independently of the aforesaid unit. 45

4. A switch plug comprising a longitudinally divided casing, a switch base, a switch mechanism mounted therein including the switch terminals, a lead wire terminal connected to one of the switch terminals, 50 a plug socket connected to the other switch terminal, the said switch base, the switch mounted thereon, the lead wire terminal and the plug socket forming a unit which is adapted to be received in recesses provided therefor in the casing and to be otherwise unconnected with the casing, a second lead wire terminal, a second plug socket, and a conductor connecting the said second lead wire terminal and plug socket, which 55 parts form a second unit adapted to be received and maintained in recesses provided therefor in the casing and otherwise unconnected with the casing and removable therefrom as a unit. 60

Signed by me this 30th day of Sept., 1921.

JOHN B. DOWNING.
